UNITED STATES PATENT OFFICE

2,615,395

TYPEHOLDER SOCKET

Peter J. Hahn, Sr., Chicago, Ill., assignor to Peter J. Hahn & Sons Company, Chicago, Ill.

Application March 25, 1949, Serial No. 83,449

1 Claim. (Cl. 101—390)

1

This invention relates to a new and improved type holder socket.

Stamping or foil imprinting machines such as shown in my copending patent applications entitled Type Holding Apparatus and Foil Feeding Device for Stamping Machines and having Serial Numbers 66,460 and 66,459 respectively, employ sockets in the stamping head thereof for receiving and holding type holders. Various means have been employed to effect a locking of the holder within the socket, but few if any have possessed the combined qualities of economy and effectiveness.

It is therefore a principal object of this invention to provide means in a type holder socket for maintaining the holder against relative vertical movement and means for adjustably setting the holder in any transverse position with respect to the socket.

An important object of this invention is the provision of means in a socket for a type holder in which the holder dovetails within the socket.

Another important object of this invention is to supply a hinged shim in a type holder socket arranged in combination with a dovetail joint for the purpose of permitting easy sliding entrance of the holder into the socket and thereafter swinging the shim about its hinge to thereby lock the holder within the socket.

A still further important object of this invention is to provide shim means disposed longitudinally in the dovetail joint of a socket and having end means turned inwardly to permit sliding of an article into the socket and simultaneously pushing it to a stop for easy and accurate centering.

Other and further important objects will become apparent from the disclosures in the following specification and accompanying drawing.

In the drawings:

Figure 1 is a perspective view of the type holder socket of this invention.

Figure 2 is a perspective view of the underside of the device of Figure 1.

Figure 3 is a sectional view taken on the line 3—3 of Figure 2.

Figure 4 is a sectional view taken on the line 4—4 of Figure 1.

Figure 5 is a sectional view taken on the line 5—5 of Figure 1.

Figure 6 is a front elevational view of the shim employed in this invention.

Figure 7 is an end view of the shim of Figure 6.

Figure 8 is a top plan view of the shim of Figures 6 and 7.

2

As shown in the drawings:

The reference numeral 10 indicates generally a vertically reciprocable member which is mounted in a stamping machine such as shown in my copending application on a foil feeding device for stamping machines mentioned above. A type holder socket 11 is mounted as a unitary part with, and at the bottom of the vertically reciprocable member 10. The holding socket 11 is equipped with a channel slot 12 on its underside having dovetail or undercut sides 13 and 14 respectively. A type holder 15 is adapted to slide within the channel 12 by reason of its having mating dovetailed end projections 16 and 17. Type is put in the holder 15 and upon moving the entire unit downwardly, an impression will be made on any object positioned on a platen provided therefor.

In order to make a uniform impression the type must remain fixed in an identical position on each impressing movement thereof. To provide maximum utility the type holder must also be capable of being easily removed from the socket holder and the type holder must then be capable of reinsertion for resuming its original position. In view of this it is necessary that the fit of the type holder within the holding socket be relatively snug. Because of the snug fit, means is provided to permit easy insertion or removal of the type holding member and still accomplish a tight fit between the holder and socket by a simply operated mechanism interposed between the socket and type holder.

A shim 18 is placed between and within the dovetailed members 14 and 17. This shim or locking member, as it is employed in this apparatus, is shown in detail in Figs. 6, 7 and 8. The shim is provided with a tapered end 19 and is further provided with a threaded hole at 20. As best shown in Figures 1 and 2, the shim 18 is fastened to the type holding socket in the position indicated by means of a screw type rivet 21 passing through and threadedly engaging the hole 20 in the him and through an aligned opening 22 in the socket side wall. The screw rivet 21 holding the shim to the socket 11 is somewhat loose so that the shim 18 may have some relative movement with respect to the type holder 11. In addition to the hinging about the loose rivet the shim is made of a sufficiently resilient brass or other metallic material permitting it a certain amount of bending adjacent the rivet attachment. As shown in Figure 2 the tapered end 19 is located flush with the end 23 of the type holder socket 11. A type holder may thereupon be easily inserted within the channel 12

without being hindered by the shim within the channel 12. Thereafter the typeholder is guided to a snug tight fitting position within the channel 12. By the time the type holder is pushed entirely within the channel so that it completely fills the length of the channel, the type holder lies parallel to the channel side walls and the shim 18 is supporting the type holder loosely but firmly in position within the type holder socket 11.

A thumb screw 24 has a threaded shank portion 25 which engages a threaded aperture in the side 26 of the type holder socket 11 at a position spaced longitudinally from the rivet supporting member 21. The thumb screw 24 is tightened after insertion of the type holder and the shim 18 swings about the rivet support 21 as a hinge or bending support and the looseness permits some translational movement of the shim 18 inwardly against the type holder 15. After this movement of the shim 18 the type holder is locked in position and is not removable from the type holder socket 11 except by loosening of the thumb screw 24. Loosening of the thumb screw 24 permits the shim 18 to move laterally away from the type holder 15.

As best shown in Figure 5 the rivet 21 is shown as constituting a screw having a head 27 and a threaded shank portion 28 passing through the type holding socket and engaging the shim 18. The thumb screw adjustment is disclosed in greater detail in Figure 4 wherein the threaded shank portion 25 is shown abutting the shim 18 and moving it against the type holding member 15.

The shim 18 is further provided with a bent end portion 29 which, as shown in Figure 2, projects inwardly of the channel 12 and thus forms a stop for the type holder 15 and prevents accidental sliding of the type holder entirely through the channel socket. In other words the type holder is accurately centered within the type holding socket 11 by reason of the bent end 29 forming a stop. The type holder 15 with its type therein is adapted for sliding into the type holder socket 11 at the end 23 thereof, over the bevelled end 19 of the shim 18, and continues until the end thereof strikes the stop or abutment 29 on the far end of the shim 18. When this occurs the type holder is centered within the stamping head 23, and the operator is assured that the impressions made by the stamping machine will occur in an identical location on the platen or other base upon which the imprinting is made regardless of the number of operations of the machine or the number of times the type holder is changed. When the type holder is fully centered in the socket 11, the thumb screw 24 is tightened, causing the threaded shank 25 to move the shim 18 against the type holder 15 and effect a locking of the type holder in its centered position in the type holder socket 11.

The operation of the device of this invention is simple. The operator or user of the stamping machine sets the desired type in a type holder and thereafter inserts it by sliding into the holding socket provided on the underside of the vertically movable stamping head. The shim 18 interposed between the angularly shaped undercut in the socket and the similarly shaped angular projection on the type holder is equipped with a bevelled forward edge to permit easy passage of

the type holder. Sliding of the type holder continues until it strikes the stop 29 on the inner end of the shim. The type holder is now centered within the head and it is locked in that position by a tightening of the thumb set screw 24. The shim thereupon tightens against the type holder, holding it fixed with respect to the stamping head socket. Repeated impressions may now be made with the stamping machine and there is every assurance that the type will remain in fixed position and that it will be properly centered on the platen.

Many details of construction may be varied throughout a wide range without departing from the principles disclosed herein, and I therefore do not propose limiting the patent granted hereon otherwise than as necessitated by the appended claim.

What is claimed is:

20 A type holder and socket therefor including a type holder having upwardly and outwardly extending tongue members and a socket including a head portion having a channel on the underside thereof having cooperative engaging groove portions for mating with the tongue members of the type holder, means interposed between the type holder and the socket for effecting a locking of the type holder in the channel, said means including a rigid, non-resilient shim adapted to lie within said channel along one side thereof, said head portion having spaced first and second openings on the side thereof and extending into said channel, the first of said openings being closely positioned one end of the channel and the second 30 of said openings being positioned midway between the ends of the channel, screw fastening means passing loosely through the first of said openings and attached to said shim and adapted to hold the shim in position somewhat loosely with respect to said head portion, screw means threadedly engaging the second of said openings in said head portion and adapted to abut said shim centrally of its length and effect lateral movement of the shim, whereby the shim is tightened against 40 the type holder and thus locking the type holder with the socket head, said shim being tapered at its end portion adjacent its attachment to said screw fastening means at the first opening to permit easy sliding of the type holder within the socket, and said shim at its other end being provided with a laterally and inwardly bent end portion forming a centering abutment of the type holder within the type holder socket.
